United States Patent Office

Des. 188,818
Patented Sept. 13, 1960

188,818

BOTTLE

Jack A. Northrup, Whittier, William D. Rhodes, Long Beach, and Alfred D. Sterges, Los Angeles, Calif., assignors to Purex Corporation, Ltd., South Gate, Calif., a corporation of California

Filed Jan. 4, 1960, Ser. No. 58,923

Term of patent 14 years

(Cl. D58—8)

Fig. 1 is a side elevational view of a bottle embodying our new design;

Fig. 2 is a side elevational view taken on line 2—2 of Fig. 1;

Fig. 3 is a top plan view thereof;

Fig. 4 is a bottom plan view thereof;

Fig. 5 is a cross-sectional view thereof taken on line 5—5 of Fig. 2; and

Fig. 6 is a fragmentary cross-sectional view thereof taken on line 6—6 of Fig. 1.

We claim:

The ornamental design for a bottle, substantially as shown.
